MODULATION SYSTEM

Murray G. Crosby, Riverhead, N. Y., assignor to
 Radio Corporation of America, a corporation of
 Delaware

Application May 1, 1942, Serial No. 441,323

9 Claims. (Cl. 179—171.5)

In this application a new and improved method and means for producing amplitude modulation, phase modulation, or carrier-eliminated amplitude modulation is disclosed.

In my improved method and means a carrier-eliminated amplitude modulated wave is produced by frequency modulating a wave which is then passed through a circuit having zero output at the carrier frequency. In this circuit the carrier is reduced substantially to zero and the side bands passed. This carrier-eliminated amplitude modulated wave may be used as such or, if preferred, carrier may be added thereto with proper phase to produce a resultant wave modulated in amplitude or in phase. As is well known, the side bands and carrier in a phase modulated wave are relatively displaced and phased 90° with respect to the same relationship in an amplitude modulated wave.

The principle used in this invention is similar to that employed in my Wave modulator disclosed in my U. S. Patent No. 2,248,745 and in my Frequency modulation receiver disclosed in Crosby application #434,509, filed March 13, 1942.

In describing my invention in detail reference will be made to the attached drawings wherein Fig. 1 illustrates by block diagram the essential features of a system arranged in accordance with my invention, while Fig. 2 shows somewhat schematically the essential features of the circuit connections of an improved modulator system arranged in accordance with my invention.

Referring to Fig. 1 the modulation input which may represent voice signals, telegraphy signals, television signals, facsimile signals, etc. appears at jack 10 and is applied from the jack to a frequency modulation system in unit 14 to produce a frequency modulated carrier. The unit 14 is assumed to include any approved frequency modulation system including a source of wave energy of carrier frequency and means for modulating the wave length of the said carrier wave energy. The frequency modulated wave is fed to unit 18 which includes a mixing tube wherein it is heterodyned with oscillations of substantially constant frequency, from a stable wave carrier source 20, and in which the difference frequency, which is an intermediate frequency, is modulated as to wave length in a manner corresponding to the modulations applied in unit 14. This difference frequency, or intermediate frequency, is passed from converter 18 through lines 19 to a series tuned circuit in unit 24 which gives zero or substantially zero output at the carrier frequency (mean intermediate frequency). The characteristic of this series tuned circuit is substantially as shown in unit 24 of Fig. 1.

As is well known the means in 24, by dropping out the carrier, converts the wave length modulations on the wave energy passed into corre-

sponding amplitude modulation so that the output of 24 is wave energy in the form of side bands modulated in amplitude and frequency. This combination of amplitude and frequency modulation is fed to unit 30 which is also fed the original modulated carrier from unit 14. In unit 30 the amplitude and frequency modulated output of 24 is heterodyned back to the carrier frequency by beating against the frequency modulated wave from 14 so that a constant frequency output is obtained in lines 34 which has the frequency of the carrier source 20.

In the heterodyning process carried out in converter 30 the frequency modulations on the wave cancel out, while the carrier is tuned or filtered out with progressively lesser alternation as the carrier frequency is departed from. The sum frequency output is selected. Such selection makes the output carrier frequency, if one were present, the same as the frequency of source 20. However, the side bands with carrier-eliminated amplitude modulation are selected and made available for utilization at lines 34. The modulation on this constant frequency wave is carrier-eliminated amplitude modulation which consists of the amplitude modulation side bands only.

This output may be used directly from lines 34, if such modulation is desired, but if phase or amplitude modulation is desired, the side bands 30 may be combined in unit 40 with the carrier from unit 20 with the proper phase relations as adjusted in unit 44. Where phase modulation output is desired from 40, the new carrier supplied from 20 through phase adjuster 40 is out of phase substantially 90° with respect to the phase position it would have for the case of amplitude modulation. The combining tubes in stage 40 are biased and adjusted for linear, class A amplifier operation.

40 In setting forth the operation of the system, reference will be made to Fig. 1 wherein is shown by block diagram the essential components of the system. The carrier source 20 feeds converter 18 which is also fed by frequency modulated oscillator 14 to produce a heterodyne output in lines 19. This output may be the sum or difference of the currents from 20 and 14. This heterodyne output is fed through a circuit in 24 which has an amplitude characteristic in accordance with the characteristic drawn in that block. Such a characteristic gives zero output at carrier frequency and rises linearly on either side. Thus as the frequency is modulated either side of the carrier frequency the output rises linearly. This superimposes carrier-eliminated amplitude modulation upon the frequency modulated wave which is passed through the circuit. This frequency modulated wave is fed to a converter in 30 where it is heterodyned with the original frequency modulation wave from 14 so that a constant-

frequency beat note of the difference or sum frequencies is obtained for the heterodyned output. The carrier-eliminated amplitude modulation remains and the carrier frequency has the frequency of carrier source 20. The output of converter 30 may be utilized directly if a carrier-eliminated amplitude modulation is desired.

If amplitude modulation with the carrier present is desired, the carrier from 20 is recombined by means of the carrier and side-band combiner 40 which is fed by the carrier and side bands. Phase adjuster 44 adjusts the phase of the carrier with respect to the side bands so that the proper relation for amplitude modulation is obtained.

If phase modulation is desired, phase adjuster 44 is set to introduce a 90° shift with respect to the setting for amplitude modulation. This follows from the well-known fact that phase modulation may be considered as amplitude modulation with the phase of the carrier shifted 90°.

In Fig. 2 I have shown circuit connections of the means shown by block diagram in Fig. 1. Modulation of the desired type is applied at jack 100 and impressed by the transformer on an electrode of the reactance tube 101. Condenser C and resistance R form the phase shifter for the reactance tube 101. The internal impedance between the anode 103 and cathode of the reactance tube is shunted across the tuned tank circuit 107 or a part thereof. The tuned tank circuit 107 is the frequency determining circuit of an oscillation generator tube 102 which is frequency modulated by the reactance tube 103 under the influence of the control potentials at 100 in a well-known manner.

This reactance tube frequency modulated is of the type disclosed in many of my prior applications. See, for example, U. S. Patent No. 2,279,659, dated April 14, 1942. The operation of this reactance tube modulator, therefore, is well-known in this art and a detailed description thereof at this point is believed unnecessary.

This frequency modulated wave is fed by lines 110 and 112 to grids 116 and 118 of the two converter tubes 120 and 124. A carrier wave generator tube 136 with crystal 140 generates a wave of nearly fixed frequency and this wave is fed by blocking condenser 131 to the grid 144 of converter tube 124 to produce a frequency modulated intermediate frequency in the output of converter 124. This intermediate frequency output is fed from the anode 150 of tube 124 through the rejection circuit consisting of tuned circuit 152 and 154 which has the characteristics shown in unit 24 in Fig. 1. To obtain this characteristic condenser 152 and inductance 154 are series tuned to the mean frequency of the frequency modulated intermediate frequency (sum or difference) output from 124. The resulting carrier-eliminated amplitude modulated, frequency modulated wave is then fed by lines 156 to the grid 158 of tube 120 and therein heterodyned with the original frequency modulated wave fed from the tank circuit 107 to the grid 116 of tube 120 to produce a (difference or sum frequency) constant frequency amplitude modulated wave output in tube 120. This output which appears in parallel tuned circuit 160 may be utilized directly if carrier-eliminated amplitude modulation is desired. In this case the output is supplied by blocking condenser 121 to additional amplifiers and radiating means or translating means of any type.

If phase or amplitude modulation is desired, the side bands are combined with a new carrier

in tube 170. The new carrier may be derived from the constant frequency source including tube 136. The side bands are fed by lead 171 to the grid 174 of tube 170. The carrier is fed from tube 136 to the grid 176 of this tube 170 through a phase shifter consisting of a push-pull secondary winding, in the tuned circuit 177, coupled to the oscillator tank circuit 175 and to a variable resistor 178 and condenser 179. The phase adjustment is made by adjusting variable resistance 178 to a point such that the carrier is in phase with the resultant of the side bands when amplitude modulation with a carrier output is desired, or is 90° out of phase with respect to the resultant of the side bands when phase modulation output is desired. The phase modulation or amplitude modulation output is taken from the tuned output circuit 180 through blocking condenser 181.

The operation of the oscillator 136 and the mixer stages including tubes 120 and 124 is well known in the art and it is believed detailed description thereof and of the various biasing circuits, plate supply leads, chokes, etc., is unnecessary. It is noted, however, that tube 170 is adjusted and biased to operate as a linear class A amplifier.

I claim:

1. In a signalling system, a source of wave energy the wave length of which is controlled in accordance with control potentials and apparatus for deriving therefrom side band energy correspondingly modulated in amplitude only including a source of oscillations of substantially constant frequency, a mixer stage coupled to said first named source and to said second named source, a filter circuit coupled to said mixer stage, said filter having a characteristic such that its output for wave energy of a mean frequency equal to the beat of the frequencies of said second and first mentioned sources is substantially zero and increases for frequencies which depart in either direction from said mean frequency, and a second mixer stage coupled to said filter and to said first named source.

2. In a signalling system, a source of wave energy the wave length of which is controlled in accordance with control potentials and apparatus for deriving therefrom energy correspondingly modulated in phase or in amplitude including a source of oscillations of substantially constant frequency, a mixer stage coupled to said first named source and said second named source, a filter circuit coupled to said mixer stage, said filter circuit having a characteristic such that its output for wave energy of a mean frequency equal to the beat of the frequencies of said second and first mentioned sources is substantially zero and increases for frequencies which depart in either direction from said mean frequency, a second mixer stage coupled to said first source and to said filter circuit, and a combining stage coupled to said second mixer stage and to said second source.

3. A system as recited in claim 2 wherein a phase adjuster is included in said coupling between said combining stage and said second source.

4. In apparatus of the class described, a timing modulated oscillation generator and means for varying the timing of the oscillations generated in accordance with signals, a source of oscillations of substantially fixed frequency, an electron discharge mixing tube having input electrodes and an output electrode, a coupling between an

input electrode of said mixing tube and said timing modulated oscillation generator, a coupling between said source of oscillations of substantially fixed frequency and an input electrode of said mixing tube whereby timing modulated oscillations and oscillations of substantially fixed frequency are impressed on said input electrodes and heterodyned in said tube, a circuit series tuned to a beat note obtained by mixing the timing modulated oscillations and the oscillations of substantially fixed frequency coupled with the output electrode of said mixing tube, an electron discharge device having input electrodes and an output electrode, a coupling between an input electrode of said device and said timing modulated oscillation generator, a coupling between an input electrode of said discharge device and said series circuit, and a circuit coupled with the output electrodes of said device for selecting therefrom amplitude modulated energy wherefrom the carrier has been substantially suppressed.

5. In apparatus of the class described, a timing modulated oscillation generator and means for varying the timing of the oscillations generated in accordance with signals, a source of oscillations of substantially fixed frequency, an electron discharge mixing tube having a plurality of control electrodes and an output electrode, a coupling between one control electrode of said mixing tube and said timing modulated oscillation generator, a coupling between said source of oscillations of substantially fixed frequency and another control electrode of said mixing tube whereby timing modulated oscillations and oscillations of substantially fixed frequency are impressed on said control electrodes and heterodyned in said tube, a circuit series tuned to a beat note obtained by mixing the timing modulated oscillations and the oscillations of substantially fixed frequency coupled with the output electrode of said mixing tube, an electron discharge device having control grid electrodes and an output electrode, a coupling between a control electrode of said device and said timing modulated oscillation generator, a coupling between another control electrode of said discharge device and said series circuit, and a circuit coupled with the output electrode of said device for selecting therefrom amplitude modulated energy wherefrom the carrier has been substantially suppressed.

6. In apparatus of the class described, a timing modulated oscillation generator and means for varying the timing of the oscillations generated in accordance with signals, a source of oscillations of substantially constant frequency, an electron discharge mixing tube having input electrodes and an output electrode, a coupling between an input electrode of said mixing tube and said timing modulated oscillation generator, a coupling between said source of oscillations of substantially constant frequency and an input electrode of said mixing tube whereby timing modulated oscillations and oscillations of substantially constant frequency are impressed on said input electrodes and heterodyned in said tube, a circuit series tuned to a beat note obtained by mixing the timing modulated oscillations and the oscillations of substantially constant frequency coupled with the output electrode of said mixing tube, an electron discharge device

having input electrodes and an output electrode, a coupling between an input electrode of said device and said timing modulated oscillation generator, a coupling between an input electrode of said device and said series circuit, whereby timing modulated oscillations from said generator and wave energy from the output of said mixing tube are impressed on the input electrodes of said device and beat frequency energy appears on said 10 output electrode of said device, an additional combining tube having input electrodes and output electrodes, a coupling between said source of oscillation of substantially constant frequency and the input electrodes of said additional combining tube, a coupling between the input electrodes of said additional combining tube and the output electrode of said device, and connections for deriving from the output electrodes of said additional combining tube signal modulated 15 energy.

7. Apparatus as recited in claim 6 wherein a phase adjusting network is included in the coupling between the source of oscillations of substantially constant frequency and the input electrodes of the additional combining tube.

8. In apparatus of the class described, a timing modulated oscillation generator and means for varying the timing of the oscillations generated in accordance with signals, a source of oscillations of substantially fixed frequency, an electron discharge mixing tube having a plurality of control electrodes and an output electrode, a coupling between a control electrode of said mixing tube and said timing modulated oscillation generator, a coupling between said source of oscillations of substantially constant frequency and a control electrode of said mixing tube whereby timing modulated oscillations and oscillations of substantially fixed frequency are impressed on 30 said control electrodes and heterodyned in said tube, a circuit series tuned to a beat note obtained by mixing the timing modulated oscillations and the oscillations of substantially fixed frequency coupled with the output electrode of said mixing tube, an electron discharge device having control grid electrodes and an output electrode, a coupling between a control electrode of said device and said timing modulated oscillation generator, a coupling between a control electrode 35 of said discharge device and said series circuit, whereby timing modulated oscillations from said generator and wave energy from the output of said mixing tube are impressed on the control electrodes of said device and beat frequency energy appears on said output electrode of said device, an additional combining tube having two control electrodes and output electrodes, a coupling between said oscillation generator of substantially fixed frequency and a control electrode 40 of said additional combining tube, a coupling between a control electrode of said additional combining tube and the output electrode of said device, and connections for deriving from the output electrodes of said additional combining tube signal modulated energy.

9. Apparatus as recited in claim 8 wherein a phase adjusting network is included in the coupling between the source of oscillations of substantially constant frequency and the input electrodes of the additional combining tube.

70 MURRAY G. CROSBY.
